UNITED STATES PATENT OFFICE

2,112,064

METHOD AND APPARATUS FOR TRANSFORMER TAP CHANGING UNDER LOAD

Louis F. Blume, Pittsfield, Mass., assignor to General Electric Company, a corporation of New York

Application January 21, 1937, Serial No. 121,619

10 Claims. (Cl. 171—119)

My invention relates to transformer tap changing and more particularly to a new and improved method and apparatus for transformer tap changing under load in heavy duty circuits.

5 The standard way of changing taps under load on large power transformers is as follows: The transformer current is initially divided between two branch conductors which are each connected to the same tap on one of the transformer windings. A switch then interrupts the current in one branch conductor. A tap change is then made by the transformer ratio adjuster with respect to that conductor. During this time all the transformer current flows through the second branch 10 conductor. The circuit through the first conductor is then reclosed, resulting in a redivision of the transformer current between the two branch conductors. Then a second switch interrupts the current in the second branch conductor and the ratio adjuster makes another tap change 15 with respect to the second branch conductor. The circuit through the second branch conductor is then reclosed. In this way taps are changed in a step by step manner along a row of transformer tap contacts without at any time breaking the main circuit.

Heretofore, such arrangements have required the use of at least two current interrupting arcing contactors or switches, one being connected in 20 each of the two branch circuits or conductors. These contactors have to be capable of carrying the full circuit current continuously so that they are relatively large and expensive and they require a relatively high contact pressure between their 25 contacts.

In accordance with my invention, I separate the two functions of (1) selecting which of the two branch conductor circuits is to be opened and (2) interrupting the current in the selected 30 branch. In doing this, I use one or more main current carrying switches for selecting which of the two branch circuits is to be opened, and I utilize a separate switch or contactor for performing the current interrupting function.

35 The selector switch or switches need not be designed for arcing duty and they may consist of little more than low resistance separable contacts which are capable of continuously carrying the transformer current. The current interrupting switch need only be an arcing element and need not be designed to carry the full circuit current continuously. It is therefore possible to construct it of light material and for relatively 40 low contact pressure.

45 It is to be noted that I utilize but a single cur-

rent interrupting contactor instead of two as heretofore.

An object of my invention is to provide a new and improved method and apparatus for transformer tap changing under load. 5

Another object of my invention is to provide a new and improved way of heavy duty transformer tap changing under load.

My invention will be better understood from the following description taken in connection with 10 the accompanying drawing and its scope will be pointed out in the appended claims.

Referring now to the single figure of the accompanying drawing, I have shown therein diagrammatically an embodiment of my invention as 15 applied to a power transformer 1. As shown, this transformer has a primary winding 2 connected to a supply circuit 3 and a secondary winding 4 connected to a load circuit 5. The winding 4 is provided with a plurality of tap contacts 6. A suitable ratio adjuster of any well known construction is arranged to make selective connections between tap contacts 6 and a pair of branch circuit conductors 8 and 9. The mechanical details of one such ratio adjuster are shown in 20 Patent No. 1,538,204, issued June 8, 1936 on an application of H. O. Stephens et al. and assigned to the assignee of the present application. The branch conductors 8 and 9 are arranged for selective simultaneous or individual connection to 25 the lowermost conductor of load circuit 5 by means of a main current carrying selector switch 10. This switch is really a non-current interrupting, disconnecting switch and is shown by way of example as consisting of a segmental copper disc 11 which in the position shown bridges 30 a pair of fixed contacts 12 and 13 connected respectively to the branch conductors 8 and 9. A brush contact 14 makes continuous engagement and electrical contact with the disc 11. Due to 35 the cut-away portion in the disc 11, rotation through a relatively small angle in either direction causes one or the other of the branch conductors 8 or 9 to be disconnected from the circuit 5, although it will be seen that at no time can 40 both branch conductors be simultaneously disconnected from the main load circuit.

It will be observed that switch 10 is the equivalent of the separate normally closed switches which are so interlocked that only one can be 45 opened at a time. Obviously, therefore, switch 10 may be replaced by such an arrangement.

For interrupting the current in the branch conductors 8 and 9 I provide a single arcing contactor or switch 15. This switch may be of any 50

suitable type and as shown comprises a fixed contact 16 and a movable contact 17, the latter being operable by means of a cam 18.

The ratio adjuster 7, the disc 11 and the cam 18 are preferably coupled together mechanically so that they all may be driven by a common operating means. As shown, they are all coupled together by a shaft 19 driven by a motor 20.

The inter-relation between the ratio adjuster 7, the disconnecting switch 10 and the current interrupting switch 15 is such that as the shaft 19 is turned in either direction, first the switch 15 breaks the connection through it between one or the other of the fixed contacts 12 or 13 and the common contact 14, next the current interrupting switch 15 opens, and thereafter the ratio adjuster operates to change the tap connection of the disconnected branch circuit conductor. As the rotation of the shaft 19 is continued, the switch 15 recloses first, and shortly thereafter the main current carrying switch 10 closes.

Connected in series with the branch conductors 8 and 9 are the halves 21 of a preventive reactor. Such devices are well-known and serve to limit the circulating current through the branch conductors at times when they are connected to different voltage tap contacts. When the branch conductors are connected to the same tap contact, the currents in the two halves 21 of the preventive reactor neutralize each other electromagnetically and no current limiting reactance is set up in the circuit.

By way of example, I have shown my invention as applied to an automatic voltage regulating system. The main control element is a conventional contact making voltmeter 22 connected to respond to the voltage of load circuit 5. It has a set of "raise" contacts 23 which close when the load circuit voltage is below a predetermined normal value and a set of "lower" contacts 24 which close when the circuit voltage is above the predetermined normal value. These "raise" and "lower" contacts 23 and 24 control reversing circuits for the motor 20, which is shown by way of example as a conventional reversible capacitor motor, such as is commonly used for driving the tap changing mechanism of regulating transformers. Ordinarily, of course, auxiliary relays are interposed between the contact making voltmeter contacts and the motor circuits, but for the sake of simplicity, they have been omitted from the drawing.

The operation of the illustrated embodiment of my invention is as follows:

55 Assume that power is being transmitted through the transformer 1 from the supply circuit 3 to the load circuit 5 and that for some reason the voltage of the load circuit 5 falls sufficiently below normal to cause the engagement 60 of the "raise" contacts 23. This completes a circuit for operating the motor 20. Assume that the motor 20 rotates in such a direction that copper disc 11 and cam 18 turn in a counter-clockwise direction as viewed in the drawing.

65 Before anything happens as a result of the operation of the motor and of the rotation of the disc 11 and the cam 18, all of the transformer load current will be divided between the branch conductors 8 and 9, which as shown are both connected to the same tap contact by the ratio adjuster 7. Practically all of this current will be flowing through switch 10, which is designed to carry all of this current and which has a lower resistance than the current interrupting contactor 15.

Now, as the shaft 19 starts to rotate in a counter-clockwise direction, the first thing that happens is that the disc 11 breaks contact with fixed contact 18. However, the current in branch circuit 9 is not interrupted but continues to flow through the contacts of the current interrupting switch 15 around to the fixed contact 12 and then through the disc 11 and the common contact 14 to the circuit 5. The fixed contact 12 is thus carrying the entire transformer load current. The cam 18 is so constructed that shortly after the disc 11 leaves the fixed contact 18 the current interrupting switch 15 is opened thereby interrupting the current flow through the branch conductor 9. All of the transformer current is now being carried by the branch conductor 8. The branch conductor 9 can then be connected to the next lowermost tap contact, as viewed in the drawing, either manually or by means of the ratio adjuster 7. Shortly after conductor 9 is connected to the next lowermost tap contact, the switch 15 closes thereby completing a current carrying path from the conductor 9 through the fixed contact 12 and the disc 11 to the common contact 14. Soon after the closure of the switch 15, the disc 11 will have rotated substantially 180° and will again form a bridging connection between the fixed contacts 12 and 13. The voltage of the load circuit will now have been raised by an amount corresponding to half the voltage between the tap contacts and if this is sufficient to restore the voltage to normal, the contact-making voltmeter will break the motor circuit through its "raise" contacts 23. If not, the motor 20 will continue rotating and disc 11 will soon thereafter break contact with fixed contact 12, but the current through the branch conductor 8 will continue to flow through the switch 15 to the fixed contact 13 and then through the switch 10 to the main circuit. Shortly afterwards, however, the switch 15 will again open thereby interrupting the current in the branch 8 whereupon the branch 8 can be connected by means of the ratio adjuster, or manually, to the same tap contact to which conductor 9 has been connected. The switches 15 and 10 will then close in the order mentioned and the voltage of the load circuit will be raised by one-half the difference in voltage between tap contacts. This operation will continue, first the switch 10 opening and then switch 15 opening and then the branch conductor which is not carrying current being connected to the next lowermost tap, and then the switches 15 and 16 closing in the order given and so on until the voltage has been raised to the value at which the contact-making voltmeter 22 balances.

If the voltage of the load circuit 5 is too high, the "lower" contacts of the contact-making voltmeter 24 close thereby reversing the direction of the motor 20. This does not reverse the sequence of operation of the switches 10 and 15 but merely reverses the direction of tap changing produced by the ratio adjuster. Thus, instead of connecting the branch conductors 8 and 9 successively to lower or outer tap contacts, the reversal of direction of the motor 20 causes the ratio adjuster to make successive connections in a step by step manner of the branch conductors 8 and 9 along the upper or inner tap contacts, thus lowering the voltage of circuit 5. It is to be understood, however, that before each tap change with respect to one of the branch conductors, the circuit through it is first broken by the switch 10 and then the current in it is inter- 75

rupted by the switch 15 before the tap change is made. This operation continues until the voltage is restored to normal whereupon the contact making voltmeter 22 balances.

5 While I have shown and described a particular embodiment of my invention, it will be obvious to those skilled in the art that changes can be made without departing from my invention, and therefore I aim in the appended claims to 10 cover all such changes and modifications as fall within the true spirit and scope of my invention.

What I claim as new and desire to secure by Letters Patent of the United States is:

1. The method of transformer tap changing 15 under load which consists of connecting two branch conductors of a circuit to one or more taps on a transformer winding, opening a connection between one of said conductors and said circuit while maintaining a connection between 20 said conductors, opening said connection between said conductors, connecting said disconnected conductor to another tap on said winding, reconnecting said conductors together, and reconnecting the disconnected conductor directly 25 to said circuit.

2. The method of transformer tap changing under load which consists of connecting two conductors that connect to taps on a transformer winding to one side of a circuit through a switch, 30 opening the connection between one of said conductors and said circuit through said switch while maintaining a conducting path for current between said conductor and said circuit through a second switch, opening said path by means of 35 said second switch, connecting said conductor to another tap on said transformer, closing said second switch and closing the connection between said conductor and said circuit through the first switch.

40 3. In a circuit for transformer tap changing under load, a power circuit, a transformer winding provided with a plurality of taps, a ratio adjuster for selectively connecting a pair of conductors to said taps, main current carrying selector switching means for connecting both of 45 said conductors to said power circuit and for selectively disconnecting either one of said conductors from said circuit, and a current interrupting arcing contactor for maintaining a current conducting path between said circuit and the 50 conductor disconnected therefrom by said switching means until after said switch opens.

4. In a circuit for transformer tap changing under load, a transformer winding provided with 55 taps, a ratio adjuster for causing a pair of conductors selectively to make connection to said taps, a switch for selectively connecting both or either one of said conductors to said circuit, and a contactor for maintaining a connection between 60 said circuit and whichever conductor is disconnected from said circuit by said switch, said contactor being coupled to said switch so as to open after said switch opens.

5. In a transformer tap changing under load 65 circuit, a transformer winding provided with a plurality of taps, a ratio adjuster for selectively connecting a pair of conductors with a plurality of said taps, a switch having two fixed contacts and a movable contact, said fixed contacts being connected respectively to said conductors, said 70 movable contact being arranged selectively to

engage both or either of said fixed contacts, and a contactor connected between said fixed contacts, said switch and contactor being so correlated that the contactor is only open when the movable contact of the switch is engaging but one 5 of the fixed contacts.

6. In a circuit for transformer tap changing under load, a power circuit, a transformer winding provided with taps, a ratio adjuster for selectively connecting a pair of conductors to various 10 taps on said winding, fixed contacts connected respectively to said conductors, a movable switch member connected to said circuit and adapted selectively to bridge said fixed contacts or to engage either one of said fixed contacts alone, a 15 contactor connected between said fixed contacts, and means for driving said ratio adjuster and movable member and contactor in such sequence that after the movable member disengages one 20 of said fixed contacts, the contactor opens, then said ratio adjuster connects the conductor whose fixed contact has been disengaged to another tap, then the contactor closes and finally the movable member is moved to a position bridging 25 said fixed contacts.

7. In an automatic regulating system, a power circuit, a transformer provided with a ratio adjuster for connecting a pair of conductors to taps on a winding thereof, a non-current interrupting disconnecting switch for selectively connecting 30 either one or both of said conductors to said circuit, a current interrupting switch for interrupting the current in whichever conductor has been disconnected from said circuit by said disconnecting switch, and means responsive to an operating 35 condition which is controlled by the ratio of said transformer for driving said ratio adjuster and said two switches in such a manner that the ratio adjuster only operates when the current interrupting switch is open and the current interrupting 40 switch is only open when the disconnecting switch is open.

8. In combination, a source of current provided with taps, an electric circuit, two conductors, 45 means for connecting said two conductors selectively to said taps, means for connecting said two conductors selectively to said circuit, and a switch connected to said two conductors and completing when in closed position a short circuited loop with said last mentioned means.

50 9. A system for transformer tap changing under load comprising, a set of fixed contacts, two movable contacts, means to connect selectively said two movable contacts to said fixed contacts, a load circuit, means to connect selectively said 55 two movable contacts to said load circuit, a single switch arranged to transfer when opened the current from either one of said movable contacts to the other, the direction of transfer being predetermined by a condition of said last means.

10. In combination, a transformer winding with taps, two movable contacts arranged to engage 60 said taps selectively, an impedance in series with at least one of said movable contacts, a switch to connect said movable contacts selectively to a load circuit, and a switch for bridging across the conductors of said two contacts at a point intermediate to said impedance and their connection to said load circuit.
